UNITED STATES PATENT OFFICE.

WILLIAM ELLIS, OF LYTHAM, ENGLAND.

SHAPE RETAINER FOR MEN'S SOFT HATS.

Application filed June 22, 1921. Serial No. 479,698.

To all whom it may concern:

Be it known that I, WILLIAM ELLIS, a subject of the King of Great Britain, residing at Lytham, Lancaster County, England, have invented a new and useful Shape Retainer for Men's Soft Hats, of which the following is a specification.

In the wearing of a velour, felt, cloth, straw or similar hats or caps of a soft character it is found in course of use that by having frequently to put on and take off the hat there is a tendency for the front part of the hat to get out of shape by reason of the wearer grasping the crown instead of the brim thus forming dents where the hat is gripped by the hand and these dents or misshapements take away the smart appearance of the hat and make it look old and worn.

20 The rear or back part of the hat generally retains its shape because it is not handled in the above manner in the raising or putting on or taking off the hat from the head.

25 Now the object of the present invention is to overcome or prevent the aforesaid defects by providing simple and inexpensive means adapted to retain the front, and if desired the back, part of the hat in its correct shape.

In the accompanying drawings—

Figure 1 is a side elevation of a hat having a device constructed according to the present invention applied thereto, part of the hat being broken away to show the position of the retainer or stiffener when in use.

Figure 2 is a plan or development of the device separately.

Figure 3 is an edge view thereof.

40 Figure 4 is a similar view to Figure 2 illustrating a modification in the construction of the device and

Figure 5 is a similar view to Figure 4 illustrating a further modification.

45 Referring to Figures 1 to 3 of the drawings, 1 represents a plate or sheet of any suitable material which may be shaped as shown, or it might be of any other suitable shape and this plate 1 is designed to be inserted in the inside front part of the hat 2 between the leather or cloth band 3 and the body of the hat 2 in the manner shown in

Figure 1, said plate 1 being retained in position by said band 3.

If desired the plate or stiffener 1 may be 55 further fixed in position by stitches or any suitable adhesive or it may be embodied in the material of which the hat is formed during the manufacture of the same.

If desired the plate may be shaped in conformity with the usual shape of the hat as first worn or it may be embossed in order to give to the hat the required shape.

The device is preferably constructed of celluloid on account of its lightness and 65 springiness and it may be perforated to further lighten its weight as shown at 6 Figure 2 and to provide means for ventilation and to prevent any curling or bulging of the device which might be caused by the 70 varying heat or perspiration of the head but it may also be constructed of any other suitable substance such as cardboard or other material.

The device might if desired be of skeleton formation and constructed of wire of any suitable character.

In the example given at Figure 4 the device is constructed of a wire frame 1 having stretched across the same wire or other 80 suitable gauze 1^a. Or it might be a network of intermeshing wire of any suitable gauge.

In the example given at Figure 5 the device consists of a body 1 and a tail piece 4 connected to the body 1 by means of bars 85 or struts 5. In use the tail piece 4 is inserted between the band 3 and the body of the hat 2 when the body 1 of the device will conform to the shape of the hat 2 with a certain amount of outward pressure. 90

It will be obvious that the device may be further modified without departing from the principle of the invention.

Having now particularly described and ascertained the nature of my said invention 95 and in what manner the same is to be performed I declare that what I claim is:—

A shape retainer for men's hats comprising a flat sheet of flexible material having its upper edge formed to correspond 100 with the interior transverse contour of the front portion of the top of the hat and being provided on its lower edge with cut away portions on opposite sides of the cen-

ter so as to provide depending supporting members at each end and at the center, in alignment with each other when the sheet is in a flattened condition, the said sheet adapted to be bent to conform to the interior contour of the vertical walls of the hat and having the supporting members inserted be-

tween the sweat band and vertical walls at the front thereof so as to prevent collapse of the same.

In testimony whereof I have signed my name to this specification.

WILLIAM ELLIS.
